Specification for Design.

Patented June 21, 1921.

Application filed December 21, 1920. Serial No. 432,366. Term of patent 14 years.

To all whom it may concern:

Be it known that we, EUGENE M. DOWNEY and CHARLES P. HEPP, both citizens of the United States, residing at Waukesha, in the county of Waukesha and State of Wisconsin, have invented a new, original, and ornamental Design for an Automobile Signal-Lamp, of which the following is a specification, reference being had to the accompanying drawing, forming part thereof.

Figure 1 represents a face view of an automobile signal lamp showing our new design, and

Fig. 2 is an end view of the same.

We claim:

The ornamental design for an automobile signal lamp, as shown.

In testimony that we claim the foregoing we have hereunto set our hands at Waukesha, in the county of Waukesha and State of Wisconsin.

EUGENE M. DOWNEY.
